CONTROL FOR FANS, BLOWERS, AND PUMPS

Thomas Bosanko Collins, Strathbungo, Glasgow,
ScotlandApplication June 12, 1933, Serial No. 675,499
In Great Britain July 7, 1932

8 Claims. (Cl. 230—114)

This invention relates to improved means of controlling the volumetric output and discharge pressure of fans, blowers, pumps and the like of both propeller and centrifugal type, by varying the intake, being more particularly applicable to units of the free intake type, and units running at constant speed.

Another form of this invention is the subject matter of applicant's copending application Serial No. 675,832, filed June 14, 1933.

The improved controlling means according to the present invention are of the kind in which a curved deflector provided in an entrance chamber to the casing, from which the fluid enters the eye of the fan, is adapted to be adjusted to vary the throat of the entrance chamber in such a manner that the delivery of the fluid into the said casing shall be substantially in the peripheral direction of the casing.

According to the present invention the controlling means for varying the throat of the entrance chamber comprise two curved plates which are hinged together, the one plate forming a wall of the entrance chamber and the other plate a portion of the wall of the inlet casing facing the eye of the fan, the reduction of the throat being effected by approaching the two hinged plates towards each other and its increase by moving them away from each other.

The invention also consists in providing each of two entrance chambers provided at diametrically opposite sides of a substantially cylindrical casing adjacent to the eye of the fan with a pair of curved hinged plates as referred to and connecting the two pairs of plates by means which will enable them to be simultaneously operated.

Another feature of the invention consists in using the curved hinged plate forming one of the walls of the entrance chamber in conjunction with a stationary curved plate constituting the opposite wall of the said chamber, the two walls forming a smoothly converging nozzle with two convex sides facing one another.

A still further feature of the invention consists in continuing the stationary curved wall of each of two diametrically opposite entrance chambers by a stationary wall curved in the opposite direction and forming a portion, preferably one quarter, of the inlet casing facing the eye of the fan, and adapting the free end of each of the hinged plates forming a movable portion of the wall of the casing to move along the said stationary wall of the inlet casing.

The invention also consists in the improved con-

struction of fan or the like as hereinafter described, more particularly with reference to the accompanying drawings, in which:

Figure 1 shows an end view of the improved fan, half in elevation and half in section;

Figure 2 shows an elevation thereof, partly in section along the line A—B in Figure 1, and

Figures 3 and 4 are respectively an elevation and a cross-section of the two hinged plates, shown fully opened out.

Referring to the drawings, *a* is the fan casing, adjacent to the eye *a'* of which there is provided an air inlet casing *b*, to which air is admitted through two diametrically opposite air entrance chambers *c*, *c'*. The air inlet casing *b* and the entrance chambers *c* are formed between the fan casing *a* and a plate *d*. *e* and *f* are curved plates, each extending substantially over an arc of 90°, fixed exactly diametrically opposite one another to the fan casing and plate *d* by means of angle irons *g*. The curved plates *e* and *f* form stationary walls of the inlet casing *b* and they are respectively extended by plates *e'* and *f'* which are curved in the opposite direction and are also fixed to the fan casing and the plate *d* by means of the angle irons *g*. The extensions *e'*, *f'* form stationary walls of the entrance chambers *c*.

The throat *c'* of each of the entrance chambers *c* is varied by means of two curved plates *h*, *h'* which are hinged together at *i*, the plate *h* forming a movable wall of the entrance chamber *c* and the plate *h'* a movable wall of the inlet casing *b*; these movable walls and the respective stationary walls *e'*, *f'* of the entrance chambers face each other with their convex sides. The free end of the plate *h* is bent over to form a kind of a guiding rod *j* which is provided at its ends with ferrules *j'* adapted to engage and be guided between curved ledges *k*, *k* provided on the fan casing and the plate *d*.

According to a modification, the free end of the plate *h* may be pivotally connected to one end of preferably two swinging arms, the other end of each of which is connected to a fixed pivot, so that the turning of the swinging arms around the latter will cause their ends connected to the plate *h* to move along an arc of a circle and thereby positively guide the said plate along the required path. The swinging arms may be mounted in the entrance chambers *c* or on the other side of the plates *h* so as to lie outside the flow.

The free end of the plate *h'* is formed with a straight end *h''* which moves in contact with the stationary curved plate *e* (or *f*) of the inlet casing *b* during the variations of the throat *c'* be-

tween the entrance chambers *c* and the inlet casing *b*, the said movement being guided by lugs *l* provided on the plate *h'* and moving along the circular flange *a²* provided at the eye of the fan casing.

In order to vary the two throats to an equal extent, the two pairs of hinged plates are adapted to be operated simultaneously. Use is preferably made for this purpose of an external, centrally pivoted two-arm lever *m*, which engages at its ends with the pivots *i'* of the hinged plates, the said pivots passing through slots *d'* formed in the plate *d* and extending over circular arcs of 90° near the throats of the entrance chambers of the fluid. It is, however, to be understood that any other suitable means may be used instead.

The pair of hinged plates *h*, *h'* has been shown, on the left-hand entrance chamber, seen in Figure 1 in four different positions, in each of which the entrance chamber has the form of a smoothly converging nozzle with two sides of convex shape facing one another.

When the hinged portions are moved into their extreme positions, the inlet casing *b* adjacent to the fan eye is closed, being substantially cylindrical, and at intermediate points between the fully open and the fully shut positions, the inlet casing forms what is substantially a cylinder with openings disposed diametrically opposite and extending in a direction parallel to the axis of the cylinder. This construction of the entrance chambers ensures that at all times, except when the nozzles are fully open, the inflow to the inlet casing or chamber *b* is substantially tangential to a circle concentric with the axis of rotation of the impeller.

Although the invention has been described above in connection with an arrangement having two entrance chambers, I wish it to be understood that the invention is not limited to the number of chambers used and that the direction of the air entering the nozzles formed in the entrance chambers may be either in or against the direction of rotation of the impeller.

According to a modification, four pairs of hinged plates may be used instead of two, as shown, two pairs of which are kept in the fully open position and stationary while the other two pairs are moved as required. Thus, for instance, when it is desired to reduce the outer pressure, the movable pairs of hinged plates which are preferably arranged opposite one another are moved from their full open position to the position corresponding to the required pressure and when it is desired to increase the outward pressure, the said two pairs are again moved to their full open position and kept stationary while the other two pairs are moved to close nozzles so that the direction of the air entering from the nozzles is against the direction of rotation of the impeller. Thus only two pairs of plates would be moved from their full open position at a time. A similar arrangement may of course be used for three or more nozzles.

It is to be understood that the invention is not limited to fans and blowers, being also applicable to pumps, and that the details of construction may otherwise be varied without in any way departing from the scope of the invention as claimed in the appended claims.

What I claim is:—

1. Means for controlling the volumetric output and discharge pressure of a fluid machine having an eye, comprising an inlet casing facing the

eye of the machine and having two stationary walls at diametrically opposite sides around portions of the said eye, two entrance chambers at diametrically opposite sides of the said inlet casing, means for varying the throat between the said inlet casing and two entrance chambers, the said means comprising for each entrance chamber two curved plates which are hinged together, the one plate forming a wall of the entrance chamber and the other plate a portion of the wall of the inlet casing, the non-hinged end of the latter plate being movable along one of the said stationary walls of the inlet casing and the hinged end thereof being movable around a portion of the said eye which is not surrounded by the said stationary wall, and means for connecting the pair of plates of one entrance chamber with the pair of plates of the other entrance chamber so as to enable them to be operated simultaneously.

2. Means for controlling the volumetric output and discharge pressure of a fluid machine as claimed in claim 1, in which the means for the simultaneous operation of the two pairs of curved plates is arranged outside the machine and consists of a two-armed lever, the free ends of which are connected to the pivots of the hinged plates.

3. Means for controlling the volumetric output and discharge pressure of a fluid machine having an eye comprising an entrance chamber, one of the walls of which consists of a stationary curved plate and inlet casing facing the eye of the machine and having a stationary curved wall around a portion of the said eye, means for varying the throat between the entrance chamber and the inlet casing, the said means comprising two curved plates which are hinged together, the one plate forming a wall of the entrance chamber opposite the wall constituted by the said stationary curved plate and the other plate a movable portion of the wall of the inlet casing, the non-hinged end of the latter plate being movable along the said stationary curved wall of the inlet casing and a hinged end thereof being movable around the portion of the said eye which is not surrounded by the said stationary curved wall, whereby the said two opposite walls of the entrance chamber form a smoothly converging nozzle with two convex sides facing one another.

4. Means for controlling the volumetric output and discharge pressure of a machine as claimed in claim 3, in which the stationary curved wall of the inlet casing forms a continuation of the stationary curved plate of the entrance chamber and is curved in the opposite direction with respect thereto.

5. Means for controlling the volumetric output and discharge pressure of a machine as claimed in claim 3, in which the stationary curved wall of the inlet casing forms a continuation of the stationary curved plate of the entrance chamber and is curved in the opposite direction with respect thereto and in which a portion of the hinged curved plate moving along the stationary wall of the inlet casing is made substantially straight near the non-hinged end thereof.

6. Means for controlling the volumetric output and discharge pressure of a machine having an eye comprising an inlet casing facing the eye of the machine, and having a number of stationary walls around portions of said eye, a plurality of entrance chambers to the said inlet casing and means for varying the throat between the inlet casing and each of the entrance chambers, said means comprising for each entrance chamber two

5 curved plates which are hinged together, the one plate forming a wall of the entrance chamber and the other plate a portion of the wall of the inlet casing, the non-hinged end of the latter plate being movable along a stationary wall of the inlet casing and the hinged end thereof being movable around a portion of the eye which is not surrounded by a stationary wall, the said means for varying the throat being capable of being 10 operated independently for each entrance chamber so that some of the pairs of hinged plates can be kept in the fully opened position while the other can be moved to reduce or increase the throat as required.

15 7. Means for controlling the volumetric output and discharge pressure of a fluid machine having an eye comprising an entrance chamber, an inlet casing facing the eye of the machine and having a stationary wall around a portion of the said eye, means for varying the throat between the entrance chamber and the inlet casing, the said means comprising two curved plates which are hinged together, the one plate forming a wall of 20 the entrance chamber and the other plate a portion of the wall of the inlet casing, the non-hinged end of the latter plate being movable along the said stationary wall of the inlet casing 25

and the hinged end thereof being movable around that portion of the said eye which is not surrounded by the said stationary wall, and means for guiding the hinged curved plate forming a portion of the movable wall of the inlet casing along the periphery of the eye of the machine.

5 8. Means for controlling the volumetric output and discharge pressure of a fluid machine having an eye comprising an entrance chamber, an inlet casing facing the eye of the machine and having a stationary wall around a portion of the said eye and means for varying the throat between the entrance chamber and the inlet casing, the said means comprising two curved plates which are hinged together, the one plate forming a wall 10 of the entrance chamber, and the other plate a portion of the wall of the inlet casing, the non-hinged end of the latter plate being movable along the said stationary wall of the inlet casing and the hinged end thereof being movable around that portion of the said eye which is not surrounded by the said stationary wall and means for guiding the free end of the curved hinged plate forming a wall of the entrance chamber along a curved path.
